CLAIM

The ornamental design for a tactical gear stand, as shown and described.

DESCRIPTION

FIG. 1 is a front elevation view of a tactical gear stand in a collapsed state, showing the new design;

FIG. 2 is a back elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a perspective view thereof;

FIG. 8 is a perspective view of the tactical gear stand in an expanded state; and,

FIG. 9 is another perspective view of the tactical gear stand in a collapsed state.

The broken lines in the drawings depict portions of the article that form no part of the claimed design.
